UNITED STATES PATENT OFFICE.

GEORGE H. F. HOLY, OF PITTSBURGH, PENNSYLVANIA, ASSIGNOR TO WESTINGHOUSE ELECTRIC & MANUFACTURING COMPANY, A CORPORATION OF PENNSYLVANIA.

LOCOMOTIVE.

1,287,022.

Specification of Letters Patent.

Patented Dec. 10, 1918.

Application filed May 2, 1917. Serial No. 165,853.

To all whom it may concern:

Be it known that I, GEORGE H. F. HOLY, a citizen of the United States, and a resident of Pittsburgh, in the county of Allegheny and State of Pennsylvania, have invented a new and useful Improvement in Locomotives, of which the following is a specification.

My invention relates to locomotives and particularly to electric locomotives that are provided with jack-shafts and side-rods for transmitting the driving effort of the propelling motors to the associated driving wheels.

One object of my invention is to provide a locomotive which shall be simple and rugged in construction and have the various driving parts of the running gears conveniently disposed for repair and replacement and for developing a maximum draw-bar pull.

Another object of my invention is to provide a locomotive having a single running gear or a plurality of articulated running gears pivotally connected to the cab thereof, each of the running gears being provided with a plurality of pairs of driving wheels having a fixed wheel-base, jack-shafts disposed adjacent to said driving wheels and outside the rigid wheel-base, a plurality of motors connected to the jack-shafts, and side-rods for connecting the jack-shaft to selected pairs of the driving wheels.

Another object of my invention is to provide a locomotive of the above-indicated character which shall be provided with a running gear comprising four pairs of driving wheels having a fixed wheel-base, two jack-shafts and two auxiliary trucks disposed adjacent to said driving wheels, a plurality of motors connected to said jack-shafts, and side-rods for connecting each jack-shaft to various pairs of the driving wheels.

In electrical locomotives that are adapted to replace steam locomotives that are now in service, it is essential to provide a structure which shall develop a maximum draw-bar pull and have good tracking characteristics. The propelling motors should be conveniently located relative to the driving wheels in order to obtain the maximum efficiency from the motors and transmit the driving effort of the motors to the driving wheels in a simple and economical manner.

The electrical locomotives must not only develop a greater draw-bar pull than the steam locomotives, but must be capable of being operated at various speeds with a minimum injury to the road-bed over which the vehicles are operated.

In a locomotive constructed in accordance with my invention, the motors and the driving wheels are advantageously located and are connected together in such manner as to obtain a locomotive that shall develop a maximum draw-bar pull at moderate speed and have good tracking characteristics.

In the accompanying drawing, Figure 1 is a side elevational view of a portion of a locomotive constructed in accordance with my invention; Fig. 2 is a plan view of the running gears of the locomotive illustrated in Fig. 1; Fig. 3 is a partial elevational view of a locomotive provided with a four-wheel auxiliary truck, and Fig. 4 is a fragmentary view of a modified locomotive having a single motor connected to each jack-shaft.

Referring to Figs. 1 and 2 of the drawing, a locomotive 1 is provided with a cab 2 and two articulated running gears 3 and 4, which are connected to the cab 2 by pivotal connections 5, one only of which is illustrated. Each of the running gears embodies side-frames 6 and pairs of driving wheels 7, 8, 9 and 10, which are respectively mounted on the driving axles 11, 12, 13 and 14, and have a fixed wheel-base. A pack-shaft 15, having gear-wheels 16 mounted thereon, is disposed on the side-frames adjacent to the driving wheels 7, and a similar jack-shaft 17, having gear-wheels 18 mounted thereon, is located adjacent to the driving wheels 10. Two motors 19 and 20, having armatures 21 and 22 that are tandem-mounted on a shaft 23, are located above the jack-shaft 15, and two pinions 24, which mesh with the gear wheels 16, are mounted on the opposite ends of the armature shaft 23. Two motors 25 and 26, having armatures 27 and 28 that are tandem-mounted on a shaft 29, are located above the jack-shaft 17. Two pinions 30, which mesh with the gear-wheels 18, are mounted on the opposite ends of the armature shaft 29.

Two two-wheel radial auxiliary trucks 31 and 32 are disposed outside of the jack-shafts 15 and 16 and may be connected to the side frames 6 in any convenient and approved manner.

The gear-wheels 16, which are mounted on the jack-shaft 15, are provided with cranks 34 that are connected to cranks 35 and 36 of the driving wheels 7 and 8 by means of the side-rods 37. The gear-wheels 18, which are mounted on the jack-shaft 17, are provided with driving cranks 38 that are connected to similar driving cranks 39 and 40 of the driving wheels 10 and 9 by means of side-rods 41.

The locomotive disclosed in Figs. 1 and 2 of the drawing and which is provided with two two-wheel auxiliary trucks, is preferably adapted for freight service and not for high-speed service. However, in case the locomotive is to be operated at high speed, as, for example, in passenger service, the guiding truck is provided with four wheels as is illustrated in Fig. 3 of the drawing.

Although the locomotive illustrated in the drawing is provided with articulated running gears, it is obvious that a locomotive may be constructed with a single running gear, in which case the running gear should be provided with two four-wheel auxiliary trucks.

The locomotive illustrated in Figs. 1 and 2 of the drawing is preferably provided with two propelling motors for each jack-shaft, but, if so desired, each jack-shaft may have one motor connected thereto as is illustrated in Fig. 4 of the drawing.

Modifications in the structure and arrangement and location of parts may be made within the spirit and scope of my invention and such modifications are intended to be covered by the appended claims.

I claim as my invention:

1. In an electrical locomotive, the combination with a cab and a plurality of running gears pivotally connected thereto, each of said running gears comprising four pairs of driving wheels having a fixed wheel-base, of two jack-shafts disposed adjacent to said driving wheels, a plurality of motors associated with said jack-shafts, and side-rods for joining each of said jack-shafts to two pairs of said driving wheels.

2. In an electrical locomotive, the combination with a cab, and a plurality of running gears pivotally connected thereto, each of said running gears comprising four pairs of driving wheels, of two jack-shafts disposed adjacent to said driving wheels, a plurality of motors associated with said jack-shafts, and means for joining each of said jack-shafts to two pairs of said driving wheels.

3. In an electrical locomotive, the combination with a cab and a plurality of articulated running gears pivotally connected thereto, each of said running gears comprising a plurality of pairs of driving wheels having a fixed wheel-base, of a plurality of jack-shafts disposed adjacent to said driving

wheels, a plurality of motors associated with said jack-shafts, and side-rods for severally connecting said jack-shafts to various pairs of said driving wheels.

4. In an electrical locomotive, the combination with a cab and two articulated running gears pivotally connected thereto, each of said running gears comprising four pairs of driving wheels having a fixed wheel-base, of two jack-shafts disposed adjacent to said driving wheels and outside the fixed wheel-base, two motors having tandem-mounted armatures connected to each of said jack-shafts, and side-rods for connecting each of said jack-shafts to two pairs of the driving wheels.

5. In an electrical locomotive, the combination with a cab, two articulated running gears pivotally connected to said cab, each of said running gears comprising four pairs of driving wheels having a fixed wheel-base, and two auxiliary trucks disposed adjacent to said driving wheels, of two jack-shafts disposed between said driving wheels and the auxiliary trucks, two motors having tandem-mounted armatures connected to each of said jack-shafts, and side-rods for connecting each of said jack-shafts to two pairs of driving wheels.

6. In an electrical locomotive, the combination with a running gear comprising four pairs of driving wheels having a fixed wheel-base, of two jack-shafts disposed adjacent to said driving wheels, a plurality of motors connected to said jack-shafts, and side-rods for connecting each jack-shaft to two pairs of said driving wheels.

7. In an electrical locomotive, the combination with a running gear comprising more than two pairs of driving wheels having a fixed wheel base, of a plurality of jack shafts located adjacent to said driving wheels, motors operatively connected to said jack shafts, and side rods severally connecting each jack shaft to two pairs only of said driving wheels.

8. In an electrical locomotive, the combination with a running gear comprising a plurality of pairs of driving wheels having a fixed wheel-base, and two two-wheel auxiliary trucks disposed adjacent to said driving wheels, of two jack-shafts disposed between said auxiliary trucks and the driving wheels, a plurality of motors connected to said jack-shafts, and side-rods for connecting each jack-shaft to two pairs of said driving wheels.

9. In an electrical locomotive, the combination with a running gear comprising a plurality of pairs of driving wheels having a fixed wheel-base, and a plurality of jack-shafts disposed outside the fixed wheel-base and adjacent to the driving wheels, of a plurality of motors connected to said jack-shafts, and side-rods for severally connect-

ing said jack shafts to various pairs of said driving wheels.

10. In an electrical locomotive, the combination with a running gear comprising four pairs of driving wheels having a fixed wheel-base, and two jack-shafts disposed outside the fixed wheel-base and adjacent to the driving wheels, of two motors having tan-

dem-mounted armatures connected to each of said jack-shafts, and side-rods for connecting each of said jack-shafts to two pairs of said driving wheels.

In testimony whereof, I have hereunto subscribed my name this 28th day of April, 1917.

GEORGE H. F. HOLY.
